CROSS REFERENCE TO PRIOR APPLICATION

This application is a National Stage Patent Application of PCT International Patent Application No. PCT/JP2019/010990 (filed on Mar. 15, 2019) under 35 U.S.C. § 371, which claims priority to Japanese Patent Application No. 2018-050258 (filed on Mar. 16, 2018), which are all hereby incorporated by reference in their entirety.

TECHNICAL FIELD

The present invention relates to a crane.

BACKGROUND ART

In the related art, in a crane, a load being transported is vibrating. As such a vibration, vibration of a simple pendulum having a load suspended by a leading end of the a wire rope as a mass point or a double pendulum having a hook portion as a support point occurs with an acceleration to be applied during transportation as a motive force.

Alternatively, vibration due to bending of a structure constituting a crane such as a boom and a wire rope occurs in a load transported by the crane including the boom in addition to the vibration due to the simple pendulum or the double pendulum.

The load suspended by the wire rope vibrates at a resonance frequency of the simple pendulum or the double pendulum, and is transported while vibrating at a natural frequency in a derrick direction of the boom and a natural frequency in a slewing direction and/or a natural frequency during expansion and contraction vibration due to the expansion of the wire rope.

In such a crane, an operator needs to perform an operation of canceling the vibration of the load by slewing or derricking the boom by a manual operation of an operation tool in order to stably lower the load at a predetermined position. Thus, transportation efficiency of the crane is affected by a magnitude of the vibration generated during the transportation and a skill level of the crane operator.

Accordingly, there is known a crane that suppresses the vibration of the load by attenuating a frequency component of a resonance frequency of the load from a transportation command (control signal) an actuator of the crane and improves the transfer efficiency (see, for example, Patent Literature 1).

The crane device described in Patent Literature 1 calculates the resonance frequency from a rope length (suspension length) which is a distance from a rotation center of the vibration of the wire rope to a center of gravity of the load. That is, the crane device calculates the resonance frequency for the hook (used hook) that suspends the load. The crane device generates a filter control signal by removing a component near the resonance frequency from the control signal by the filter unit.

The aforementioned crane device suppresses swing of the load by controlling an operation of the boom based on the filter control signal during the transportation of the load.

2
SUMMARY OF THE INVENTION

Problems to be Solved by the Invention

5 Incidentally, in the case of the crane described in Patent Literature 1, there is a possibility that an unused hook comes into contact with the wire rope and/or the boom that suspends the used hook due to the vibration of the unused hook that does not suspend the load during the transportation of the load.

10 An object of the present invention is to provide a crane that can reduce vibration of an unused hook during transportation.

Solutions to Problems

15 An aspect of a crane according to the present invention includes a operable function unit including at least a boom, an operation unit that receives an operation input for operating the operable function unit, an actuator that drives the 20 operable function unit, a generation unit that generates a first control signal of the actuator based on the operation input, a plurality of wire ropes, a plurality of hooks that is suspended from a leading end section of the boom by the plurality of wire ropes, respectively, a hook detection unit that detects an unused hook which does not suspend a load among the plurality of hooks, a calculation unit that calculates a resonance frequency for the wire rope suspending the detected unused hook among the plurality of wire ropes, a filter unit that generates a filter based on the resonance frequency, and generates a second control signal by filtering the first control signal using the filter, and a control unit that controls the actuator based on the second control signal.

Effects of the Invention

35 According to the present invention, vibration of an unused hook can be reduced during transportation.

BRIEF DESCRIPTION OF DRAWINGS

40 FIG. 1 is a side view illustrating an overall configuration of a crane.

FIG. 2 is a block diagram illustrating a control configuration of the crane.

45 FIG. 3 is a diagram illustrating a graph representing frequency characteristics of a notch filter.

FIG. 4 is a diagram illustrating a graph representing a control signal and a filtering control signal to which the notch filter is applied.

FIG. 5 is a side view of the crane in operation.

FIG. 6 is a flowchart of a part of vibration suppression control according to a first embodiment of the present invention.

50 FIG. 7 is a flowchart illustrating a notch filter application process.

FIG. 8 is a flowchart of a part of the vibration suppression control according to the first embodiment of the present invention.

55 FIG. 9 is a flowchart of a part of vibration suppression control according to a second embodiment of the present invention.

60 FIG. 10 is a flowchart of a part of vibration suppression control according to a third embodiment of the present invention.

DESCRIPTION OF EMBODIMENTS

65 Hereinafter, a crane 1 according to a first embodiment of the present invention will be described with reference to

FIGS. 1 and 2. In the present embodiment, the crane is a mobile crane (rough-terrain crane). However, the crane may be various cranes such as a truck crane.

As illustrated in FIG. 1, the crane 1 is a mobile crane that can move to an unspecified place. The crane 1 has a vehicle 2 and a crane device 6.

The vehicle 2 transports the crane device 6. The vehicle 2 has a plurality of wheels 3 and runs with an engine 4 as a power source. The vehicle 2 has an outrigger 5. The outrigger 5 has an overhanging beam and a jack cylinder. The overhanging beam can be expanded and contracted in a width direction of the vehicle 2 by hydraulic pressure.

The jack cylinder is fixed to a leading end section of the overhanging beam, and can be expanded and contracted in a direction perpendicular to the ground. The vehicle 2 can widen a workable range of the crane 1 by expanding and contracting the outrigger 5 in the width direction of the vehicle 2 and grounding the jack cylinder.

The crane device 6 lifts a load W with a wire rope. The crane device 6 includes a slewing base 7, a boom 9, a jib 9a, a main hook block 10, a sub hook block 11, a derrick hydraulic cylinder 12, a main winch 13, a main wire rope 14, a sub winch 15, a sub wire rope 16, and, a cabin 17.

The slewing base 7 supports the crane device 6 such that the crane device 6 can slew with respect to the vehicle 2. The slewing base 7 is provided on a frame of the vehicle 2 via an annular bearing. The slewing base 7 rotates about a center of the annular bearing. The slewing base 7 has a hydraulic type slewing hydraulic motor 8. The slewing base 7 slews in a first direction or a second direction by the slewing hydraulic motor 8. The hydraulic motor and the hydraulic cylinder that drive the boom 9 correspond to an example of an actuator. Specifically, the slewing hydraulic motor 8 corresponds to an example of an actuator.

The slewing hydraulic motor 8 is rotationally operated by a slewing valve 31 (see FIG. 2) that is an electromagnetic proportional switching valve. The slewing valve 31 can control a flow rate of hydraulic oil to be supplied to the slewing hydraulic motor 8 to any flow rate. That is, the slewing base 7 is controlled to any slewing speed via the slewing hydraulic motor 8 that is rotationally operated by the slewing valve 31. The slewing base 7 has a slewing sensor 25 (see FIG. 2) that detects a slewing position (angle) and a slewing speed of the slewing base 7.

The boom 9 supports the wire rope in a state in which the load W can be lifted. The boom 9 is constituted by a plurality of boom members. The boom 9 is expanded and contracted in an axial direction by moving each boom member by an expansion and contraction hydraulic cylinder (not illustrated). A base end of a base boom member of the boom 9 is swingably supported at substantially a center of the slewing base 7. The expansion and contraction hydraulic cylinder corresponds to an example of an actuator.

The expansion and contraction hydraulic cylinder is telescopically operated by an expansion and contraction valve 32 (see FIG. 2) that is an electromagnetic proportional switching valve. The expansion and contraction valve 32 controls a flow rate of hydraulic oil to be supplied to the expansion and contraction hydraulic cylinder to any flow rate.

That is, the boom 9 is controlled to have any boom length by the expansion and contraction valve 32. The boom 9 has an expansion and contraction sensor 26 and a weight sensor 27 (see FIG. 2). The boom 9 corresponds to an example of a operable function unit. The operable function unit may be regarded as including at least the boom 9.

The expansion and contraction sensor 26 detects a length of the boom 9. The weight sensor 27 detects a weight Wm of the load W to be added to a main hook 10a. Alternatively, the weight sensor 27 detects a weight Ws of the load W to be added to a sub hook 11a. The weight sensor 27 corresponds to an example of a suspension load detection unit.

The jib 9a is used for enlarging a lifting height and a working radius of the crane device 6. The jib 9a is held in a posture along the base boom member by a jib support section provided on the base boom member of the boom 9. A base end of the jib 9a is configured to be connectable to a jib support section of a top boom member.

The main hook block 10 and the sub hook block 11 are suspending tools for suspending the load W. A plurality of hook sheaves around which the main wire rope 14 is wound and the main hook 10a for suspending the load W are provided at the main hook block 10.

The sub hook 11a for suspending the load W is provided at the sub hook block 11. A weight of the main hook block 10 may be regarded as a weight including the hook sheaves and the main hook 10a. Alternatively, a weight of the sub hook block 11 may be regarded as a weight including the sub hook 11a.

The derrick hydraulic cylinder 12 raises and lowers the boom 9 to hold the posture of the boom 9. The derrick hydraulic cylinder 12 has a cylinder section and a rod section. An end portion of the cylinder section is swingably connected to the slewing base 7. An end portion of the rod section is swingably connected to the base boom member of the boom 9. The derrick hydraulic cylinder 12 corresponds to an example of an actuator.

The derrick hydraulic cylinder 12 is telescopically operated by a derrick valve 33 (see FIG. 2) that is an electromagnetic proportional switching valve. The derrick valve 33 can control a flow rate of hydraulic oil to be supplied to the derrick hydraulic cylinder 12 to any flow rate. That is, the boom 9 is controlled by the derrick valve 33 to any derrick speed. A derrick sensor 28 (see FIG. 2) that detects a derrick angle of the boom 9 is provided at the boom 9.

The main winch 13 and the sub winch 15 pull in (wind up) and let out (wind out) the main wire rope 14 and the sub wire rope 16. The main winch 13 has a main drum around which the main wire rope 14 is wound, and a main hydraulic motor (not illustrated) that rotationally drives the main drum. The main hydraulic motor corresponds to an example of an actuator.

The sub winch 15 includes a sub drum around which the sub wire rope 16 is wound, and a sub hydraulic motor (not illustrated) that rotationally drives the sub drum. The sub hydraulic motor corresponds to an example of an actuator.

The main hydraulic motor is rotationally operated by a main valve 34 (see FIG. 2) that is an electromagnetic proportional switching valve. The main valve 34 can control a flow rate of hydraulic oil to be supplied to the main hydraulic motor to any flow rate.

That is, the main winch 13 is controlled by the main valve 31 to have any pulling-in and letting-out speed. Similarly, the sub winch 15 is controlled by a sub valve 35 (see FIG. 2) that is an electromagnetic proportional switching valve to have any pulling-in and letting-out speed.

A main letting-out amount detection sensor 29 is provided at the main winch 13. Similarly, a sub letting-out amount detection sensor 30 is provided at the sub winch 15. The main winch 13 and the sub winch 15 correspond to an example of a operable function unit.

The main letting-out amount detection sensor 29 detects a letting-out amount $L_{ma}(n)$ of the main wire rope 14 let out from the main winch 13. The letting-out amount $L_{ma}(n)$ detected by the main letting-out amount detection sensor 29 may be regarded as a length of the main wire rope 14 let out from the main winch 13.

The sub letting-out amount detection sensor 30 detects a letting-out amount $L_{sa}(n)$ of the sub wire rope 16 let out from the sub winch 15. The letting-out amount $L_{sa}(n)$ detected by the sub letting-out amount detection sensor 30 may be regarded as a length of the sub wire rope 16 let out from the sub winch 15.

The cabin 17 covers an operator cab. The cabin 17 is mounted on the slewing base 7. The cabin 17 has the operator cab (not illustrated). An operation tool for operating the vehicle 2 to run and an operation tool for operating the crane device 6 are provided in the operator cab.

The operation tool for operating the crane device 6 includes, for example, a slewing operation tool 18, a derrick operation tool 19, an expansion and contraction operation tool 20, a main drum operation tool 21, a sub drum operation tool 22, a swing suppression switch 23, and a priority hook selection switch 24 (see FIG. 2).

Among the operation tools, a tool that receives an operation input for operating the boom 9 corresponds to an example of an operation unit. Specifically, the slewing operation tool 18, the derrick operation tool 19, and the expansion and contraction operation tool 20 correspond to an example of an operation unit. Alternatively, among the operation tools, the main drum operation tool 21 for operating the main winch 13 and the sub drum operation tool 22 for operating the sub winch 15 correspond to an example of an operation unit. Such an operation unit receives an operation input for operating the operable function unit.

The slewing operation tool 18 controls the slewing hydraulic motor 8 by operating the slowing valve 31. The derrick operation tool 19 controls the derrick hydraulic cylinder 12 by operating the derrick valve 33. The expansion and contraction operation tool 20 controls the expansion and contraction hydraulic cylinder by operating the expansion and contraction valve 32.

The main drum operation tool 21 controls the main hydraulic motor by operating the main valve 34. The sub drum operation tool 22 controls the sub hydraulic motor by operating the sub valve 35.

The swing suppression switch 23 is used in selecting whether or not to perform vibration suppression control for unused hooks. In an ON state, the swing suppression switch 23 may automatically determine the unused hook. In the ON state, the swing suppression switch 23 may perform the vibration suppression control on the determined unused hook. In the following description, the hook that suspends the load W is referred to as the used hook. Alternatively, the hook by which the load W is not suspended is called the unused hook.

The priority hook selection switch 24 is used in selecting a hook to which the vibration suppression control is preferentially applied. An operator selects a hook (hereinafter, referred to as a priority hook) to be prioritized from the main hook and the sub hook by operating the priority hook selection switch 24. The priority hook selection switch 24 may be omitted.

When the unused hook is not determinable, a control device 36 may perform the vibration suppression control on the priority hook. The operator may select the unused hook as the priority hook in advance by using the priority hook selection switch 24.

The crane 1 having the aforementioned configuration can move the crane device 6 to any position by causing the vehicle 2 to run. Alternatively, the crane 1 can change the lifting height and the working radius of the crane device 6 by changing the derrick angle of the boom 9 due to the operation of the derrick operation tool 19 and changing the length of the boom 9 due to the operation of the expansion and contraction operation tool 20.

Alternatively, the crane 1 transports the load W by slew-ing the slewing base 7 due to the operation of the slewing operation tool 18 in a state in which the load W is lifted by operating the drum operation tool (the main drum operation tool 21 or the sub drum operation tool 22) for changing a height of the used hook.

As illustrated in FIG. 2, the control device 36 controls the actuator of the crane 1 via each operation valve. The control device 36 includes a control signal generation unit 36a, a resonance frequency calculation unit 36b, and a filter unit 36c. The control signal generation unit 36a corresponds to an example of a generation unit.

The control device 36 is provided in the cabin 17. The control device 36 may actually have a configuration in which a CPU, a ROM, a RAM, and an HDD are connected via a bus. Alternatively, the control device 36 may be configured by a single chip LSI or the like.

The control device 36 may store various kinds of programs and data for controlling operations of the control signal generation unit 36a, the resonance frequency calculation unit 36b, and the filter unit 36c.

The control signal generation unit 36a is a part of the control device 36, and generates a control signal that is a speed command for each actuator. The control signal generation unit 36a acquires an operation amount (also referred to as operation-related information.) of each operation tool from the slewing operation tool 18, the derrick operation tool 19, the expansion and contraction operation tool 20, the main drum operation tool 21, and/or the sub drum operation tool 22.

The control signal generation unit 36a acquires information related to a state of the crane 1 such as the slewing position of the slewing base 7, the boom length, the derrick angle, and/or the weights W_m and W_s of the load W from the slewing sensor 25, the expansion and contraction sensor 26, the weight sensor 27, and/or the derrick sensor 28.

The control signal generation unit 36a generates a control signal C(1) of the slewing operation tool 18 based on the acquired operation-related information or the crane 1 and/or the information related to the state of the crane 1. Alternatively, the control signal generation unit 36a generates control signals C(2) to C(5) of the operating tools 18 to 22 based on the acquired operation-related information and/or the information related to the state of the crane 1. Herein-after, the control signals C(1) to C(5) are collectively referred to as a control signal C(n). n may be regarded as the number of operation tools controlled by the control signals generated by the control signal generation unit 36a. The control signal C(n) generated by the control signal generation unit 36a corresponds to an example of a first control signal.

Alternatively, the control signal generation unit 36a may acquire a signal from the swing suppression switch 23. The control signal generation unit 36a selects an unused hook, and starts the vibration suppression control. The control signal generation unit 36a selects the priority hook to which the vibration suppression control is preferentially applied

among the main hook **10a** and the sub hook **11a** based on the signal acquired from the priority hook selection switch **24**.

The resonance frequency calculation unit **36b** is a part of the control device **36**, and calculates a resonance frequency $\omega(n)$ of the swing of the load **W** by using the load **W** suspended by the main wire rope **14** and/or the sub wire rope **16** as a simple pendulum. The resonance frequency calculation unit **36b** corresponds to an example of a calculation unit.

The resonance frequency calculation unit **36b** may calculate the resonance frequency $\omega(n)$ of the swing of the main hook **10a** by using the main hook **10a** suspended by the main wire rope **14** as the simple pendulum. Alternatively, the resonance frequency calculation unit **36b** may calculate the resonance frequency $\omega(n)$ of the swing of the sub hook **11a** by using the sub hook **11a** suspended by the sub wire rope **16** as the simple pendulum. It may be considered that the resonance frequency calculation unit **36b** acquires information necessary for calculating the resonance frequency $\omega(n)$ from each element constituting the control device **36**.

The resonance frequency calculation unit **36b** may acquire the derrick angle of the boom **9** from the control signal generation unit **36a**. The resonance frequency calculation unit **36b** may acquire the letting-out amount $L_{ma}(n)$ of the main wire rope **14** from the main letting-out amount detection sensor **29**.

Alternatively, the resonance frequency calculation unit **36b** may acquire the letting-out amount $L_{sa}(n)$ of the sub wire rope **16** from the sub letting-out amount detection sensor **30**. Alternatively, when the main hook block **10** is used, the resonance frequency calculation unit **36b** may acquire a winding number of the main hook block **10** from a safety device (not illustrated).

The resonance frequency calculation unit **36b** calculates a wire length $L_{m(n)}$ (see FIG. 5) of the main wire rope **14** in a vertical direction from a position at which the main wire rope **14** is separated from the hook sheave (also referred to as a main hook sheave) to the main hook block **10**. The resonance frequency calculation unit **36b** may be regarded as an example of a wire length calculation unit.

The resonance frequency calculation unit **36b** may calculate the wire length $L_{m(n)}$ in the vertical direction based on the letting-out amount $L_{ma}(n)$ acquired from the main letting-out amount detection sensor **29**. Specifically, the wire length $L_{m(n)}$ in the vertical direction may be regarded as a value obtained by dividing the letting-out amount $L_{ma}(n)$ by the winding number (two in the case of the present embodiment) of the main hook block **10**.

The wire length $L_{m(n)}$ in the vertical direction may be regarded as the length of the main wire rope **14** equal to a distance between the main hook sheave and the main hook block **10** in the vertical direction.

Alternatively, the resonance frequency calculation unit **36b** may calculate a wire length $L_{s(n)}$ (see FIG. 5) of the sub wire rope **16** in the vertical direction from a position at which the sub wire rope **16** is separated from the hook sheave (also referred to as a sub hook sheave) to the sub hook block **11**.

The resonance frequency calculation unit **36b** may calculate the wire length $L_{s(n)}$ in the vertical direction based on the letting-out amount $L_{sa}(n)$ acquired from the sub letting-out amount detection sensor **30**. In the case of the present embodiment, since the winding number of the sub hook block is one, the wire length $L_{s(n)}$ in the vertical direction is equal to the letting-out amount $L_{sa}(n)$.

The wire length $L_{s(n)}$ in the vertical direction may be regarded as the length of the sub wire rope **16** equal to the

distance between the sub hook sheave and the sub hook block **11** in the vertical direction.

The resonance frequency calculation unit **36b** may calculate the resonance frequency $\omega(n)=\sqrt{g/L(n)}$ . . . (1) for the main wire rope **14**. The resonance frequency calculation unit **36b** may calculate the resonance frequency $\omega(n)=\sqrt{g/L_{m(n)}}$ based on a gravitational acceleration g and the wire length $L_{m(n)}$ of the main wire rope **14** in the vertical direction.

Alternatively, the resonance frequency calculation unit **36b** may calculate the resonance frequency $\omega(n)=\sqrt{g/L(n)}$ . . . (1) for the sub wire rope **16**. The resonance frequency calculation unit **36b** may calculate the resonance frequency $\omega(n)=\sqrt{g/L_{s(n)}}$ based on the gravitational acceleration g and the wire length $L_{s(n)}$ of the sub wire rope **16** in the vertical direction.

The filter unit **36c** is a part of the control device **36**, and generates notch filters $F(1)\cdot F(2)\dots F(n)$ that attenuate a specific frequency region of the control signal $C(1)\cdot C(2)\dots C(n)$ (hereinafter, simply referred to as "notch filters $F(n)$ ", where n is any number). The filter unit **36c** filters the control signal $C(n)$ by the generated notch filter $F(n)$.

The filter unit **36c** acquires the slewing position of the slewing base **7**, the boom length, the derrick angle, the weights W_m and W_s of the load **W**, the control signal $C(1)$, and the control signal $C(2)\dots$ the control signal $C(n)$ from the control signal generation unit **36a**. The filter unit **36c** acquires the resonance frequency $\omega(n)$ from the resonance frequency calculation unit **36b**.

The filter unit **36c** calculates a center frequency coefficient ω_m , a notch width coefficient ζ , and a notch depth coefficient δ of a transfer function $H(s)$ (see Equation (2) below) constituting the notch filter $F(n)$ based on information related to an operation state of the crane **1** such as the acquired slewing position of the slewing base **7**, the boom length, the derrick angle, and the weights W_m and W_s of the load **W**.

The filter unit **36c** calculates the notch width coefficient ζ and the notch depth coefficient δ corresponding to each control signal $C(n)$. The filter unit **36c** calculates the corresponding center frequency coefficient ω_m by using the acquired resonance frequency $\omega(n)$ as the center frequency $\omega_c(n)$. In the present embodiment, the filter unit **36c** calculates the center frequency coefficient ω_m , the notch width coefficient ζ , and the notch depth coefficient δ corresponding to the control signal $C(n)$, and applies these coefficients to the transfer function $H(s)$.

The filter unit **36c** generates a filter control signal $Cd(1)$ obtained by applying the notch filter $F(1)$ to the control signal $C(1)$ and attenuating a frequency component of any frequency range at any ratio by using the resonance frequency $\omega(1)$ as a reference from the control signal $C(1)$.

Similarly, the filter unit **36c** generates the filter control signal $Cd(2)$ by applying the notch filter $F(2)$ to the control signal $C(2)$. That is, the filter unit **36c** generates a filter control signal $Cd(n)$ (hereinafter, simply referred to as a "filter control signal $Cd(n)$ ") obtained by applying the notch filter $F(n)$ to the control signal $C(n)$ and attenuating the frequency component of any frequency range at any ratio by using the resonance frequency $\omega(n)$ as a reference from the control signal $C(n)$. The filter control signal $Cd(n)$ generated by the filter unit **36c** corresponds to an example of a second control signal.

The filter unit **36c** transfers the filter control signal $Cd(n)$ to the corresponding operation valve among the slewing

valve 31, the expansion and contraction valve 32, the derrick valve 33, the main valve 34, and the sub valve 35.

That is, the control device 36 controls the slewing hydraulic motor 8, the derrick hydraulic cylinder 12, the main hydraulic motor (not illustrated), and the sub hydraulic motor (not illustrated) that are the actuators, via the respective operation valves.

The control signal generation unit 36a is connected to the slewing operation tool 18, the derrick operation tool 19, the expansion and contraction operation tool 20, the main drum operation tool 21, and the sub drum operation tool 22. The control signal generation unit 36a acquires the respective operation amounts of the slewing operation tool 18, the derrick operation tool 19, the main drum operation tool 21, and the sub drum operation tool 22.

The control signal generation unit 36a is connected to the slewing sensor 25, the expansion and contraction sensor 26, the weight sensor 27, and the derrick sensor 28. The control signal generation unit 36a acquires the slewing position of the slewing base 7, the boom length, the derrick angle, and the weights Wm and Ws of the load W.

The control signal generation unit 36a is connected to the swing suppression switch 23 and the priority hook selection switch 24. The control signal generation unit 36a acquires signals from the swing suppression switch 23 and the priority hook selection switch 24.

Alternatively, the control signal generation unit 36a is connected to the resonance frequency calculation unit 36b. The control signal generation unit 36a acquires the letting-out amount Lma(n) of the main wire rope 14 from the resonance frequency calculation unit 36b.

Alternatively, the control signal generation unit 36a acquires the letting-out amount Lsa(n) of the sub wire rope 16 from the resonance frequency calculation unit 36b. Alternatively, the control signal generation unit 36a acquires the resonance frequency $\omega(n)$ from the resonance frequency calculation unit 36b.

The resonance frequency calculation unit 36b is connected to the control signal generation unit 36a. The resonance frequency calculation unit 36b acquires signals from the swing suppression switch 23 and the priority hook selection switch 24. The resonance frequency calculation unit 36b is connected to the main letting-out amount detection sensor 29, the sub letting-out amount detection sensor 30, and a safety device (not illustrated). The resonance frequency calculation unit 36b calculates the wire length Lm(n) of the main wire rope 14 in the vertical direction and the wire length Ls(n) of the sub wire rope 16 in the vertical direction.

The filter unit 36c is connected to the control signal generation unit 36a. The filter unit 36c acquires filter the slewing position of the slewing base 7, the boom length, the derrick angle, the weights Wm and Ws of the load W, and the control signal C(n). The filter unit 36c is connected to the resonance frequency calculation unit 36b. The filter unit 36c acquires the resonance frequency $\omega(n)$ from the resonance frequency calculation unit 36b.

The filter unit 36c is connected to the slewing valve 31, the expansion and contraction valve 32, the derrick valve 33, the main valve 34, and the sub valve 35. The filter unit 36c transfers the filter control signal Cd(n) corresponding to the slewing valve 31, the derrick valve 33, the main valve 34, and the sub valve 35.

Here, the notch filters F(n) will be described with reference to FIGS. 3 and 4. The notch filter F(n) is a filter that gives steep attenuation to the control signal C(n) with any frequency as a center.

As illustrated in FIG. 3, the notch filter F(n) is a filter having frequency characteristics of attenuating a frequency component with a notch width Bn which is any frequency range with any center frequency $\omega_c(n)$ as a center at a notch depth Dn that is an attenuation ratio of any frequency in the center frequency $\omega_c(n)$. That is, the frequency characteristics of the notch filter F(n) are determined by the center frequency $\omega_c(n)$, the notch width Bn, and the notch depth Dn.

The notch filter F(n) has the transfer function H(s) illustrated in the following Equation (2) below.

[Math. 1]

$$H(s) = \frac{s^2 + 2\delta\zeta\omega_n s + \omega_n^2}{s^2 + 2\zeta\omega_n s + \omega_n^2} \quad (2)$$

In Equation (2), ω_n is the center frequency coefficient ω_n corresponding to the center frequency $\omega_c(n)$ of the notch filter F(n). ζ is the notch width coefficient ζ corresponding to the notch width Bn. δ is the notch depth coefficient δ corresponding to the notch depth Dn.

In the notch filter F(n), the center frequency $\omega_c(n)$ of the notch filter F(n) is changed by changing the center frequency coefficient ω_n . Alternatively, in the notch filter F(n), the notch width Bn is changed by changing the notch width coefficient ζ . Alternatively, in the notch filter F(n), the notch depth Dn of the notch filter F(n) is changed by changing the notch depth coefficient δ .

The characteristics of the notch filter F(n) are represented by a load vibration reduction ratio Pnf determined by the notch width coefficient ζ and the notch depth coefficient δ . The load vibration reduction ratio Pnf is a ratio determined by the notch width coefficient ζ and the notch depth coefficient δ in the transfer function H(s) of the notch filter F(n).

In the control signal generation unit 36a, the control device 36 having the aforementioned configuration generates the corresponding control signal C(n) of each operation tool based on the operation amounts of the slewing operation tool 18, the derrick operation tool 19, the main drum operation tool 21, and the sub drum operation tool 22.

In the resonance frequency calculation unit 36b, the control device 36 calculates the wire length Lm(n) of the main wire rope 14 in the vertical direction based on the letting-out amount Lma(n) of the main wire rope 14 acquired from the main letting-out amount detection sensor 29. Alternatively, in the resonance frequency calculation unit 36b, the control device 36 calculates the wire length Ls(n) of the sub wire rope 16 in the vertical direction based on the letting-out amount Lsa(n) of the sub wire rope 16 acquired from the sub letting-out amount detection sensor 30.

In the resonance frequency calculation unit 36b, the control device 36 calculates the resonance frequency $\omega(n)$ for the main wire rope 14 based on the gravitational acceleration g and the wire length Lm(n) of the main wire rope 14 in the vertical direction. Alternatively, in the resonance frequency calculation unit 36b, the control device 36 calculates the resonance frequency $\omega(n)$ for the sub wire rope 16 based on the gravitational acceleration g and the wire length Ls(n) of the sub wire rope 16 in the vertical direction.

11

In the filter unit 36c, the control device 36 calculates the notch width coefficient ζ and the notch depth coefficient δ corresponding to the signal C(n) based on the control signal C(n), the swing position of the slewing base 7, the boom length of the boom 9, the derrick angle, and the weights Wm and Ws of the load W. Alternatively, the control device 36 calculates the corresponding center frequency coefficient ω_0 by using the center frequency $\omega_0(n)$ having the resonance frequency $\omega(n)$ calculated in the resonance frequency calculation unit 36b as the reference of the notch filter F(n).

As illustrated in FIG. 4, in the filter unit 36c, the control device 36 generates the filter control signal Cd(n) by applying the notch filter F(n) to which the notch width coefficient ζ , the notch depth coefficient δ , and the center frequency coefficient ω_0 are applied, to the control signal C(n).

The filter unit 36c transfers the filter control signal Cd(n) to the corresponding operation valve among the slewing valve 31, the expansion and contraction valve 32, the derrick valve 33, the main valve 34, and the sub valve 35, and controls the slewing hydraulic motor 8, the derrick hydraulic cylinder 12, the main hydraulic motor (not illustrated), and the sub hydraulic motor that are the actuators.

Next, the vibration suppression control of the unused hook in the crane 1 will be described. The vibration suppression control of the unused hook automatically detects, as a vibration control target, the unused hook from a plurality of hooks, and performs the vibration suppression control for the unused hook.

In the following embodiments, the control device 36 selects, as the unused hook, any one of the main hook 10a and the sub hook 11a in the vibration suppression control of the unused hook. That is, the control device 36 may be regarded as having a hook detection unit that selects the unused hook. Alternatively, the control device 36 sets the notch depth coefficient δ and the notch width coefficient ζ to any values corresponding to the operation state of the crane 1.

A first embodiment of the vibration suppression control will be described with reference to FIGS. 5 to 8. The control device 36 detects the unused hook in which the load W is not suspended based on a detection value of the weight sensor 27 (see FIG. 2) and the wire length of the wire rope in the vertical direction.

A reference value Wv is a load that is arbitrarily determined, and is used as a value of reference for regarding that the hook is used. It is preferable that the reference value Wv is a value set such that the vibration suppression control of the unused hook is not stable due to variations in a load. The reference value Wv corresponds to an example of a load threshold value.

The control device 36 detects the hook of the main hook 10a and the sub hook 11a whose the detection value of the weight sensor 27 (see FIG. 2) is equal to or less than the reference value Wv.

When the wire length of the wire rope in the vertical direction which suspends the detected hook is the smallest among wire lengths of other wire ropes in the vertical direction, the control device 36 sets this hook as the unused hook.

The control device 36 calculates the resonance frequency $\omega(n)$ of the unused hook from the wire length of the wire rope of the unused hook in the vertical direction. The control device 36 calculates the notch filter F(n) having the calculated resonance frequency $\omega(n)$ as the center frequency $\omega_0(n)$.

When one operation tool (hereinafter, simply referred to as a "target operation tool") of the slewing operation tool 18,

12

the derrick operation tool 19, the expansion and contraction operation tool 20, the main drum operation tool 21, and the sub drum operation tool 22 is operated, the control device 36 acquires the control signal C(n) generated based on an operation of the target operation tool. The control device 36 generates the filter control signal Cd(n) filtering the acquired control signal C(n) by the notch filter F(n).

The control device 36 controls the corresponding actuator based on the filter control signal Cd(n). Accordingly, the crane 1 suppresses vibration of the unused hook at the resonance frequency $\omega(n)$. As a result, it is possible to prevent the unused hook from coming into contact with the wire rope and/or the boom 9 of the used hook due to the vibration of the unused hook during the transportation of the load W.

Hereinafter, the vibration suppression control of the unused hook using the control device 36 will be specifically described with reference to FIGS. 6 to 8. In the following embodiments, it is assumed that the crane 1 is operated by one operation tool.

In step S110 of FIG. 6, the control device 36 may determine the priority hook to which the vibration suppression control is preferentially applied based on the operation state of the priority hook selection switch 24. The control device 36 shifts control processing to step S120.

In step S120 of FIG. 6, the control device 36 determines whether or not the swing suppression switch 23 is in the ON state.

When the swing suppression switch 23 is in the ON state ("YES" in step S120), the control device 36 shifts the control processing to step 130.

Meanwhile, when the swing suppression switch 23 is not in the ON state ("NO" in step S120), the control device 36 shifts the control processing to step S110. In step S120, when the swing suppression switch 23 is not in the ON state, the vibration suppression control of the hook (main hook 10a in the present embodiment) that suspends the load W may be started. That is, the crane 1 according to the present embodiment may be regarded as having a function of performing the vibration suppression control of the unused hook and a function of performing the vibration suppression control of the used hook.

In step S130 of FIG. 6, the control device 36 generates the control signal C(n) from an operation signal of the one operation tool. The control device 36 shifts the control processing to step S140.

In step S140 of FIG. 6, the control device 36 acquires the weight Wm to be applied to the main hook 10a and the weight Ws to be applied to the sub hook 11a from the weight sensor 27. Alternatively, in step S140, the control device 36 acquires (calculates) the wire length Lm(n) of the main wire rope 14 in the vertical direction. Alternatively, in step 140, the control device 36 acquires (calculates) the wire length Ls(n) of the sub wire rope 16 in the vertical direction. The control device 36 shifts the control processing to step S150.

In step S150 of FIG. 6, the control device 36 determines whether or not the weight Wm to be applied to the main hook 10a is equal to or greater than the reference value Wv.

When the weight Wm to be applied to the main hook 10a is equal to or greater than the reference value Wv in step S150 ("YES" in step S150), the control device 36 shifts the control processing to step S155. When the weight Wm to be applied to the main hook 10a is equal to or greater than the reference value Wv, since the load W is suspended, the main hook 10a is used.

Meanwhile, when the weight Wm to be applied to the main hook 10a is not equal to or greater than the reference

value W_v in step S150 ("NO" in step S150), the control device 36 shifts the control processing to step S165 (see a connection symbol B of FIG. 6 to a connection symbol B of FIG. 8). When the weight W_m to be applied to the main hook 10a is not equal to or greater than the reference value W_v , since the load W is not suspended by the main hook 10a, the main hook 10a is not used.

In step S155 of FIG. 6, the control device 36 determines whether or not the weight W_s to be applied to the sub hook 11a is equal to or greater than the reference value W_v .

When the weight W_s to be applied to the sub hook 11a is equal to or greater than the reference value W_v in step S155 ("YES" in step S155), the control device 36 shifts the control processing to step S160. When the weight W_s to be applied to the sub hook 11a is equal to or greater than the reference value W_v , since the load W is suspended by the sub hook 11a, the sub hook 11a is used.

When the weight W_s to be applied to the sub hook 11a is not equal to or greater than the reference value W_v in step S155 ("NO" in step S155), the control device 36 shifts the control processing to step S185. When the weight W_s to be applied to the sub hook 11a is not equal to or greater than the reference value W_v in step S155, since the load W is not suspended by the sub hook 11a, the sub hook 11a is not used.

In step S160 of FIG. 6, the control device 36 selects the priority hook as the hook to which the vibration suppression control is applied. The control device 36 shifts the control processing to step S200.

In step S185 of FIG. 6, the control device 36 determines whether or not the wire length $L_s(n)$ of the sub wire rope 16 in the vertical direction is the smallest among the wire lengths of the other wire ropes in the vertical direction.

When the wire length $L_s(n)$ of the sub wire rope 16 in the vertical direction is the smallest among the wire lengths of other wire ropes in the vertical direction in step S185 ("YES" in step S185), the control device 36 shifts the control processing to step S190.

When the wire length $L_s(n)$ of the sub wire rope 16 in the vertical direction is not the smallest among the wire lengths of other wire ropes in the vertical direction in step S185 ("NO" in step S185), the control device 36 shifts the control processing to step S195.

In step S190 of FIG. 6, the control device 36 selects the sub hook 11a as the unused hook (that is, the hook to which the vibration suppression control is applied). The control device 36 shifts the control processing to step S200.

In step S195 of FIG. 6, the control device 36 selects the priority hook as the hook to which the vibration suppression control is applied. The control device 36 shifts the control processing to step S200.

In step S200 of FIG. 6, the control device 36 starts vibration suppression control process A using the notch filter $F(n)$. The control device 36 shifts the control processing to step S210 (see FIG. 7). When vibration suppression control process A using the notch filter $F(n)$ is completed, the control device 36 shifts the control processing to step S110 (see FIG. 6).

FIG. 7 is a flowchart of vibration suppression control process A using the notch filter $F(n)$. In step S210 of FIG. 7, the control device 36 calculates the resonance frequency $\omega(n)$ of the target wire rope based on the wire rope (hereinafter, referred to as a wire length of a target wire rope in the vertical direction) of the wire rope in the vertical direction which suspends the hook (hereinafter, referred to as the target hook) selected as the hook to which the vibration suppression control is applied. The control device 36 shifts the control processing to step S220.

When the target hook is the main hook 10a in step S210, the target wire rope is the main wire rope 14, and the wire length of the target wire rope in the vertical direction is the wire length $L_m(n)$ of the main wire rope 14 in the vertical direction.

Meanwhile, when the target hook is the sub hook 11a in step S210, the target wire rope is the sub wire rope 16, and the wire length of the target wire rope in the vertical direction is the wire length $L_s(n)$ of the sub wire rope 16 in the vertical direction.

In step S220 of FIG. 7, the control device 36 generates the notch filter $F(n)$ by applying the notch width coefficient ζ , the notch depth coefficient δ , and the center frequency coefficient $\omega(n)$ corresponding to the resonance frequency $\omega(n)$ calculated according to the operation state of the crane 1 to the transfer function $H(s)$ (see Equation (2)) of the notch filter $F(n)$. The control device 36 shifts the control processing to step S230.

In step S230 of FIG. 7, the control device 36 generates the filter control signal $C_d(n)$ by filtering the generated control signal $C(n)$ by the notch filter $F(n)$. The control device 36 shifts the control processing to step S240.

In step S240 of FIG. 7, the control device 36 transfers the generated filter control signal $C_d(n)$ to the operation valve corresponding to the operation tool. As stated above, the control device 36 controls the actuators (for example, the slewing hydraulic motor 8, the expansion and contraction hydraulic cylinder, and the derrick hydraulic cylinder 12) based on the filter control signal $C_d(n)$.

That is, the control device 36 corresponds to an example of a control unit that controls the actuator based on the second control signal. The control device 36 completes vibration suppression control process A using the notch filter $F(n)$. Thereafter, the control device 36 shifts the control processing to step S110 (see FIG. 6).

FIG. 8 is a flowchart of processing to be performed after shifting from the connection symbol B of FIG. 6. In step S165 of FIG. 8, the control device 36 determines whether or not the weight W_s to be applied to the sub hook 11a is equal to or greater than the reference value W_v .

When the weight W_s to be applied to the sub hook 11a is equal to or greater than the reference value W_v in step 165 ("YES" in step S165), the control device 36 shifts the control processing to step S170. When the weight W_s to be applied to the sub hook 11a is equal to or greater than the reference value W_v in step S165, the sub hook 11a is used.

Meanwhile, when the weight W_s to be applied to the sub hook 11a is not equal to or greater than the reference value W_v in step S165 ("NO" in step S165), the control device 36 shifts the control processing to step S180. When the weight W_s to be applied to the sub hook 11a is not equal to or greater than the reference value W_v in step S165, the sub hook 11a is not used.

In step S170 of FIG. 8, the control device 36 determines whether or not the wire length $L_m(n)$ of the main wire rope 14 in the vertical direction is the smallest among the wire lengths of other wire ropes in the vertical direction.

When the wire length $L_m(n)$ of the main wire rope 14 in the vertical direction is the smallest among the wire lengths of other wire ropes in the vertical direction in step S170 ("YES" in step S170), the control device 36 shifts the control processing to step S175.

Meanwhile, when the wire length $L_m(n)$ of the main wire rope 14 in the vertical direction is not the smallest among the wire lengths of other wire ropes in the vertical direction in step S170 ("NO" in step S170), the control device 36 shifts the control processing to step S180.

15

In step S175 of FIG. 8, the control device 36 selects the main hook 10a as the unused hook (that is, the hook to which the vibration suppression control is applied). The control device 36 shifts the control processing from a connection symbol C of FIG. 6 to step S200 (see FIG. 6).

In step S180 of FIG. 8, the control device 36 selects the priority hook as the hook to which the vibration suppression control is applied. The control device 36 shifts the control processing from the connection symbol C of FIG. 6 to step S200 (see FIG. 6).

As stated above, the crane 1 performs the vibration suppression control corresponding to the operation state of the crane 1 by not only selecting the hook by using the weights Wm and Ws of the load W to be added to each hook as the reference but also automatically selecting the hook that have a small wire length in the vertical direction and is difficult to suppress vibration by a manual operation. Accordingly, the unused hook of the plurality of hooks can transport the load W without coming into contact with the wire rope or the boom 9 corresponding to the used hook due to the vibration.

Next, a second embodiment of the vibration suppression control of the unused hook in the crane 1 will be described with reference to FIGS. 5 and 9.

The control device 36 detects the unused hook based on the wire length of the wire rope in the vertical direction. When a difference L(n) (see FIG. 5) between the wire length Lm(n) of the main wire rope 14 in the vertical direction and the wire length Ls(n) of the sub wire rope 16 in the vertical direction is equal to or greater than a reference value Ld, it is difficult to manually perform the vibration suppression control. Thus, in the case of the present embodiment, the crane 1 automatically selects the unused hook by using a condition in which the difference L(n) is equal to or greater than the reference value Ld as one condition, and performs the vibration suppression control on the selected unused hook. The reference value Ld may be a value that is arbitrarily set as a value for determining whether or not manual vibration suppression control can be performed.

In the following description of the vibration suppression control according to the second embodiment, detailed description of the same control processing as the vibration suppression control according to the first embodiment described with reference to FIGS. 1 to 8 will be omitted. In FIG. 9, the same reference signs as those in FIG. 6 are assigned to the same control processing as the vibration suppression control according to the first embodiment. Hereinafter, the vibration suppression control according to the second embodiment will be described focusing on points different from the vibration suppression control according to the first embodiment.

As illustrated in FIG. 5, when the difference L(n) between the wire length Lm(n) of the main wire rope 14 in the vertical direction and the wire length Ls(n) of the sub wire rope 16 in the vertical direction is equal to or greater than the reference value Ld, the control device 36 uses, as the unused hook, the hook corresponding to the wire rope of which the wire length in the vertical direction is the smallest among the plurality of wire ropes. The vibration suppression control is performed on the unused hook, and thus, the crane 1 suppresses the vibration of the unused hook at the resonance frequency $\omega(n)$. As a result, the unused hook is prevented from coming into contact with the wire rope and/or the boom 9 that suspends the used hook due to the vibration of the unused hook during the transportation of the load W. The reference value Ld corresponds to an example of a length threshold value.

16

Hereinafter, the vibration suppression control of the unused hook using the control device 36 according to the second embodiment will be specifically described with reference to FIG. 9. It is assumed that the crane 1 is operated by one operation tool.

The control processing of steps S110, S120, and S130 of FIG. 9 is the same as the vibration suppression control according to the first embodiment.

In step S140 of FIG. 9, the control device 36 acquires 10 (calculates) the wire length Lm(n) of the main wire rope 14 in the vertical direction. Alternatively, in step S140, the control device 36 acquires (calculates) the wire length Ls(n) of the sub wire rope 16 in the vertical direction. The acquisition method (calculation method) of the wire length 15 Lm(n) in the vertical direction and the wire length Ls(n) in the vertical direction is as described above. Alternatively, in step S140, the control device 36 may acquire the weight Wm to be applied to the main hook 10a and the weight Ws to be applied to the sub hook 11a from the weight sensor 27. The 20 control device 36 shifts the control processing to step S310.

In step S310 of FIG. 9, the control device 36 determines whether or not the difference L(n) between the wire length Lm(n) of the main wire rope 14 in the vertical direction and the wire length Ls(n) of the sub wire rope 16 in the vertical 25 direction is equal to or greater than the reference value Ld($|Lm(n)-Ls(n)| \geq Ld$).

When the difference L(n) between the wire length Lm(n) of the main wire rope 14 in the vertical direction and the wire length Ls(n) of the sub wire rope 16 in the vertical direction 30 is equal to or greater than the reference value Ld in step S310 (in step S310, "YES"), the control device 36 shifts the control processing to step S320.

Meanwhile, when the difference L(n) between the wire length Lm(n) of the main wire rope 14 in the vertical 35 direction and the wire length Ls(n) of the sub wire rope 16 in the vertical direction is not equal to or greater than the reference value Ld in step S310 ("NO" in step S310), the control device 36 shifts the control processing to step S340.

In step S320 of FIG. 9, the control device 36 determines 40 whether or not the wire length Lm(n) of the main wire rope 14 in the vertical direction is the smallest among the wire lengths of the other wire ropes in the vertical direction.

When the wire length Lm(n) of the main wire rope 14 in the vertical direction is the smallest among the wire lengths 45 of other wire ropes in the vertical direction in step S320 ("YES" in step S320), the control device 36 shifts the control processing to step S330.

Meanwhile, when the wire length Lm(n) of the main wire rope 14 in the vertical direction is not the smallest among the wire lengths of other wire ropes in the vertical direction in step S320 ("NO" in step S320), the control device 36 shifts the control processing to step S350.

In the case of the present embodiment, when the wire length Lm(n) of the main wire rope 14 in the vertical 50 direction is not the smallest among the wire lengths of the other wire ropes in the vertical direction in step S320, the wire length Ls(n) of the sub wire rope 16 in the vertical direction is the smallest among the wire lengths of other wire ropes in the vertical direction.

In step S330 of FIG. 9, the control device 36 selects the main hook 10a as the unused hook (that is, the hook to which the vibration suppression control is applied). The control device 36 shifts the control processing to step S200.

In step S350 of FIG. 9, the control device 36 selects the 55 sub hook 11a as the unused hook (the hook to which the vibration suppression control is applied). The control device 36 shifts the control processing to step S200.

In step S340, the control device 36 selects the priority hook as the hook to which the vibration suppression control is applied. The control device 36 shifts the control processing to step S200.

As described above, in the present embodiment, when the difference in the wire length in the vertical direction between the wire ropes that suspend the hooks is equal to or greater than the reference value Ld, the crane 1 automatically selects, as the target hook, the hook whose wire length in the vertical direction is the smallest among the wire lengths of the other wire ropes in the vertical direction. The vibration suppression control corresponding to the operation state of the crane 1 is performed on the target hook. Accordingly, the vibration of the unused hook among the plurality of hooks is suppressed. As a result, the unused hook is prevented from coming into contact with the wire rope and/or the boom 9 that suspends the used hook due to the vibration of the unused hook during the transportation of the load W.

Hereinafter, a third embodiment of the vibration suppression control of the unused hook in the crane 1 will be described with reference to FIGS. 5 and 10. In the present embodiment, the control device 36 detects the unused hook based on the detection value of the weight sensor 27.

Hereinafter, the vibration suppression control of the unused hook using the control device 36 according to the third embodiment will be specifically described with reference to FIG. 10. It is assumed that the crane 1 is operated by one operation tool.

In the following description of the vibration suppression control according to the third embodiment, detailed description of the same control processing as the vibration suppression control according to the first embodiment described with reference to FIGS. 1 to 8 will be omitted. In FIG. 10, the same reference signs as those in FIG. 6 are assigned to the same control processing as the vibration suppression control according to the first embodiment. Hereinafter, the vibration suppression control according to the third embodiment will be described focusing on points different from the vibration suppression control according to the first embodiment.

The control processing of step S110, step S120, and step S130 of FIG. 10 is the same as the vibration suppression control according to the first embodiment.

In step S140 of FIG. 10, the control device 36 acquires the weight Wm to be applied to the main hook 10a and the weight Ws to be applied to the sub hook 11a from the weight sensor 27. Alternatively, in step S140, the control device 36 may acquire (calculate) the wire length Lm(n) of the main wire rope 14 in the vertical direction. Alternatively, in step S140, the control device 36 may acquire (calculate) the wire length Ls(n) of the sub wire rope 16 in the vertical direction. The control device 36 shifts the control processing to step S410.

In step S410 of FIG. 10, the control device 36 determines whether or not the weight Wm to be applied to the main hook 10a is equal to or greater than the reference value Wv.

When the weight Wm to be applied to the main hook 10a is equal to or greater than the reference value Wv in step S410 ("YES" in step S410), the control device 36 shifts the control processing to step S420. When the weight Wm to be applied to the main hook 10a is equal to or greater than the reference value Wv, the main hook 10a is used.

Meanwhile, when the weight Wm to be applied to the main hook 10a is not equal to or greater than the reference value Wv in step S410 ("NO" in step S410), the control device 36 shifts the control processing to step S440. When

the weight Wm to be applied to the main hook 10a is not equal to or greater than the reference value Wv, the main hook 10a is not used.

In step S420 of FIG. 10, the control device 36 determines whether or not the weight Ws to be applied to the sub hook 11a is equal to or greater than the reference value Wv.

When the weight Ws to be applied to the sub hook 11a is equal to or greater than the reference value Wv in step S420 ("YES" in step S420), the control device 36 shifts the control processing to step S430. When the weight Ws to be applied to the sub hook 11a is equal to or greater than the reference value Wv in step S420, the sub hook 11a is used.

Meanwhile, when the weight Ws to be applied to the sub hook 11a is not equal to or greater than the reference value Wv in step S420 ("NO" in step S420), the control device 36 shifts the control processing to step S470. When the weight Ws to be applied to the sub hook 11a is not equal to or greater than the reference value Wv in step S420, the sub hook 11a is not used.

In step S430 of FIG. 10, the control device 36 selects the priority hook as the hook to which the vibration suppression control applied. The control device 36 shifts the control processing to step S200.

In step S470 of FIG. 10, the control device 36 selects the sub hook 11a as the unused hook (that is, the hook to which the vibration suppression control is applied). The control device 36 shifts the control processing to step S200.

In step S440 of FIG. 10, the control device 36 determines whether or not the weight Ws to be applied to the sub hook 11a is equal to or greater than the reference value Wv.

When the weight Ws to be applied to the sub hook 11a is equal to or greater than the reference value Wv in step S440 ("YES" in step S440), the control device 36 shifts the control processing to step S450. When the weight Ws to be applied to the sub hook 11a is equal to or greater than the reference value Wv in step S440, the sub hook 11a is used.

Meanwhile, when the weight Ws to be applied to the sub hook 11a is not equal to or greater than the reference value Wv in step S440 ("NO" in step S440), the control device 36 shifts the control processing to step S460. When the weight Ws to be applied to the sub hook 11a is not equal to or greater than the reference value Wv in step S440, the sub hook 11a is not used.

In step S450 of FIG. 10, the control device 36 selects the main hook 10a as the unused hook (that is, the hook to which the vibration suppression control is applied). The control device 36 shifts the control processing to step S200.

In step S460 of FIG. 10, the control device 36 selects the priority hook as the hook to which the vibration suppression control is applied. The control device 36 shifts the control processing to step S200.

As described above, in the present embodiment, the crane 1 automatically selects the unused hook (target hook) by using the weights Wm and Ws of the load W to be applied to each hook as references. The vibration suppression control corresponding to the operation state of the crane 1 is performed on the target hook. Alternatively, when the unused hook is not selectable, the crane 1 preferentially applies the vibration suppression control to the priority hook determined in advance. That is, the crane 1 selectively applies the vibration suppression control to any one hook of the plurality of hooks. Accordingly, the unused hook is prevented from coming into contact with the wire rope and/or the boom 9 that suspends the used hook due to the vibration of the unused hook during the transportation of the load W.

19

The aforementioned embodiments may be appropriately combined and implemented within a technically consistent range. Alternatively, although it has been described in the vibration suppression control of the unused hook according to each of the above-described embodiments that the crane 1 attenuates the resonance frequency $\omega(n)$ of the control signal $C(n)$ by the notch filter $F(n)$, any filter such as a low-pass filter, a high-pass filter, or a band-stop filter that attenuates a specific frequency may be used. Alternatively, in the vibration suppression control of the unused hook according to the present embodiment, the crane 1 may be configured to control not to apply the notch filter $F(n)$ when the priority hook is selected.

Alternatively, in the control device 36, means for determining the unused hook is not limited to the aforementioned means. For example, a worker may detect, as the unused hook, a hook specified by specification means provided at the crane 1. The specification means may be the priority hook selection switch 24.

Alternatively, the control device 36 may determine the unused hook, for example, based on data captured by a camera provided at the crane 1 (specifically, the leading end section of the boom 9). Such a camera may be provided such that the main hook 10a and the sub hook 11a can be simultaneously captured. In addition, the control device 36 may detect the unused hook based on information acquired from various detection devices provided at the crane 1.

The aforementioned embodiments merely illustrate examples of a representative embodiment, and can be implemented by being variously modified without departing from the gist of one embodiment. Alternatively, the technical scope of the present invention is indicated by the description of the claims. The technical scope of the present invention also includes inventions having an equivalent relationship with the inventions described in the claims.

- The invention claimed is:
1. A crane comprising:
a operable function unit including at least a boom;
an operation unit that receives an operation input for
operating the operable function unit;
an actuator that drives the operable function unit;
a generation unit that generates a first control signal of the
actuator based on the operation input;
a plurality of wire ropes;
a plurality of hooks that is suspended from a leading end
section of the boom by the plurality of wire ropes,
respectively;
a hook detection unit that detects an unused hook which
does not suspend a load among the plurality of hooks;
a calculation unit that calculates a resonance frequency
for the wire rope suspending the detected unused hook
among the plurality of wire ropes;
a filter unit that generates a filter based on the resonance
frequency, and generates a second control signal by
filtering the first control signal due to use of the filter;
and
a control unit that controls the actuator based on the
second control signal.
  2. The crane according to claim 1, further comprising:
a load detection unit that detects loads acting on the
plurality of hooks,
wherein the hook detection unit detects the unused hook
based on the detected loads.
  3. The crane according to claim 2,
wherein the hook detection unit uses, as the unused hook,
the hook whose detected load is the smallest among the
plurality of hooks.
  4. The crane according to claim 2, further comprising:
a wire length calculation unit that calculates a length of a
portion of each of the plurality of wire ropes which is
suspended from the leading end section of the boom in
a vertical direction,
wherein the hook detection unit uses, as the unused hook,
the hook whose detected load is equal to or less than a
load threshold value and is suspended by the wire rope
of which the length in the vertical direction is the
smallest among the plurality of hooks.
  5. The crane according to claim 1, further comprising:
a wire length calculation unit that calculates a length of a
portion of each of the plurality of wire ropes which is
suspended from the leading end section of the boom in
the vertical direction,
wherein the hook detection unit detects the unused hook
based on the calculated length in the vertical direction.

21

6. The crane according to claim 5,
wherein the hook detection unit uses, as the unused hook,
the hook suspended by the wire rope of which the
length in the vertical direction is the smallest among the
plurality of wire ropes.
7. The crane according to claim 5,
wherein, when a difference between a length of a first wire
rope, which is the wire rope whose length in the vertical direction is the longest, in the vertical direction and a
length of a second wire rope, which is the wire rope
whose length in the vertical direction is the smallest, in
the vertical direction is equal to or greater than a length
threshold value, the hook detection unit uses, as the
unused hook, the hook suspended by the second wire
rope.
8. The crane according to claim 1,
wherein the actuator includes at least one actuator of an
expansion and contraction actuator for expanding and

5

10

15

22

contracting the boom, a derricking actuator for derrick-
ing the boom, and a slewing actuator for slewing the
boom.

9. The crane according to claim 1,
wherein the operable function unit includes a plurality of
winches that is provided so as to correspond to the
plurality of wire ropes, respectively, and lets out and
pulls in the corresponding wire ropes, respectively, and
the actuator includes a plurality of winch actuators that is
provided so as to correspond to the plurality of
winches, respectively, and drives the corresponding
winches, respectively.
10. The crane according to claim 1,
wherein the filter has a function of attenuating a frequency
component of a predetermined frequency range using
the resonance frequency as a reference at a predeter-
mined ratio from the first control signal.
